UNITED STATES PATENT OFFICE.

CHARLES E. CARPENTER, OF NEW YORK, N. Y.

APPARATUS FOR CONTROLLING TENSION.

Original application filed October 18, 1921, Serial No. 508,547. Divided and this application filed October 18, 1921. Serial No. 508,548.

To all whom it may concern:

Be it known that I, CHARLES E. CARPENTER, a citizen of the United States, and resident of New York city, in the county of New York and State of New York, have invented certain new and useful Improvements in Apparatus for Controlling Tension, of which the following is a specification.

10 The general object of my present invention is to provide improved means for controlling the tension of a travelling web of material. This invention was particularly devised, and is especially adapted for use 15 in controlling the tension of a web of paper as it is fed into a newspaper printing press, a waxing machine, slitting rolls, or other apparatus to which paper is supplied. The invention, however, is not necessarily 20 limited to use with webs of paper but is generally useful where it is desirable to maintain a constant tension on web or strand-like material as the latter is being drawn into or through apparatus.

25 In carrying out my invention I put the web or strand-like material under the desired tension by transmitting through the material the force required for driving a pump, and regulate, as by variably throttling the pump outlet, the differential between the pressure at the pump inlet and the pressure at the pump outlet as required to make the driving force proportional to the tension desired. Specific objects of my 30 invention are to provide ample and effective power transmitting connections to the pump proper from the web, and a simple and effective valve mechanism for regulating the compressor outlet pressure.

40 The various features of novelty which characterize my invention are pointed out with particularity in the claims annexed to and forming a part of this specification. For a better understanding of the invention, 45 however, and the advantages possessed by it, reference should be had to the accompanying drawings and descriptive matter in which I have illustrated and described preferred embodiments of my invention.

50 Of the drawings:

Fig. 1 is a side elevation;

Fig. 2 is a section taken on the line 2-2 of Fig. 1;

Figs. 3 and 4 are views taken similarly to Figs. 1 and 2 respectively, illustrating 55 a modified construction;

Fig. 5 is a section on the line 5-5 of Fig. 2; and

Fig. 6 is a view taken similarly to Fig. 1 illustrating a modified form of control valve 60 mechanism.

In the drawings A represents the framework of a printing press or like apparatus provided with open bearings A' for the ends of the spindle B for a roll B' of paper B² 65 which is drawn from the roll by the feeding mechanism of the machine, conventionally illustrated as comprising a pair of rolls A¹⁰. A² represents the usual guides along which the spindle of a fresh roll being placed in 70 the machine may be rolled into the bearings A'. The necessary tension is impressed on the web of paper B² running from the supply roll to the feed rolls A¹⁰ by means of a frictional driving connection between the 75 periphery of the roll B' and a pump C. The pump C may be either a pump for liquid as oil or water, or a pump for gas, and may be either a reciprocating pump or a rotary pump. Advantageously, however, 80 the pump is a rotary air compressor of the positive displacement type, and in the drawings I have shown a well known form of this type of compressor comprising a rotary body C⁶ with vanes or blades C⁷ pivotally 85 connected thereto and working on a cylindrical pump chamber C⁵ which is eccentrically disposed with respect to the rotating shaft C' of the pump.

The driving connection between the pump 90 shaft C' and the periphery of the roll B' comprises a pair of belts D, one at each end of the pump. Each belt D runs over a pulley D' secured to the corresponding end of the pump shaft C', and a pulley D² 95 journalled at the end of a corresponding arm E pivotally connected to a fixed support which, advantageously as shown, is the housing of the pump C. Each arm E is proportioned and arranged that the underside of 100 the corresponding belt will move from the position shown in full lines of Fig. 1 to that shown in dotted lines of the same figure and remain in contact with the periphery of the roll as the latter is unwound and diminishes in diameter. Each arm E is pro-

vided with an extension E' from which is suspended an adjustable weight F, and the parts are so relatively proportioned and arranged that an approximately constant contact pressure between each belt D and the periphery of the roll is maintained as the belt moves from the position shown in full lines to that shown in dotted lines in Fig. 1.

By providing two belts D instead of a single belt I am able to obtain the necessary compressor driving force when the roll is a full length roll, without subjecting the roll to unnecessary pressure when the roll is only half length. Ordinarily the total tension from the web needs be but half of what it should be when the roll is of full length, and with the roll of half length one of the belts may be held out of engagement with the roll.

The force required to drive the compressor, and thereby the tension put upon the web, is controlled by a valve G throttling the compressor outlet and thereby controlling the pressure differential between the pump inlet and the pump outlet. The valve G as shown comprises a casing formed with two chambers G' and G² connected by a port G³. The chamber G' is connected directly to the outlet of the compressor C, and the chamber G² is provided with outlet ports G⁵. The outlet ports G⁵ are formed in the wall of a cylindrical extension G⁴ of the chamber G² in axial alignment with the port G³. When the valve member H is in its fully closed position the inner end H' of the valve member closes the port G³, and the valve portion H² closes the port G⁵, and the parts are preferably so proportioned and arranged that the valve member H must move appreciably away from the position in which it closes the ports G³ before the portion H² begins to uncover the ports G⁵. The valve member H is urged toward its closed position by a spring I located in a spring housing forming an extension of the guide member G⁶ which is open at its outer end. The spring I acts between the valve member H and a spring follower K which may be moved toward or away from the valve member, to vary the tension of the spring I, by means of a screw spindle threaded through the outer end of the casing G⁶ and provided at its outer end with a hand wheel K². Advantageously, as shown, the valve chamber G² is connected to a small pressure equalizing reservoir G⁴.

In operation the compressor C is operated through the belt or belts D at a speed proportional to the speed of travel of the web B² drawn away from the supply roll B', and the tension of the web B² is due very largely to the throttling effect of the controlling valve G. Of course a portion of the web tension is due to friction losses

in the bearings for the roll spindle, in the pump, and in the driving connection between the pump and the periphery of the roll B', but with suitably designed apparatus these friction losses create but a small portion of the total tension required.

The tension may readily be varied to accommodate different kinds or weights of paper or other varying conditions of operation by rotating the hand wheel K² and thereby adjusting the tension of the spring I. As the speed of the web changes in starting and stopping the apparatus and the volume of air passing through the pump correspondingly varies, the movable valve member H moves toward and away from its fully closed position, but if the spring I be made long enough so that these movements of the valve member H do not materially change the tension of the spring I, the pressure at the compressor outlet may be maintained practically constant while the compressor is in operation, regardless of speed of the compressor and the volume of air passing through it. In consequence the compressor impresses practically the same force on the roll tending to retard its rotation at high speeds as at low speeds.

At the instant of starting the apparatus into operation from a condition of rest, however, the compressor opposes no initial retarding force on the roll except that due to friction, for when the compressor stops operation, the pressure at its outlet falls almost instantly to an equality with the pressure of the atmosphere by reason of the inevitable leakage from the system. The fact that the compressor exerts no resistance to the initial movement of the roll in starting other than friction resistance is advantageous because the inertia of the roll and the frictional resistance to starting the web into motion puts ample tension on the roll at that time. It is to be understood, of course, that the frictional resistance to starting roll B into rotation from a condition of rest is greater than the frictional resistance to the rotation of the roll after the latter is rotating. A small fraction of a turn of the roll is sufficient, however, to build up a pressure at the discharge of the pump which creates an appreciable tension upon the paper. This quick increase in tension is especially advantageous in preventing over travel of the roll and consequent festooning of the web in "inch" operations in which the web must be intermittently advanced a few inches at a time.

The small volumetric capacity preferably provided between the compressor chamber C⁵ and the port G³ facilitates a quick building up of the tension creating drag of the compressor as the latter starts into operation. This quick building up of a substantial tension in starting may be augmented,

as shown, by making the portion H' of the valve member H exposed to the pressure in the compressor outlet when the valve member H closes the port G^3 , smaller than the portion exposed after the port G^3 is opened. The chamber L serves as a pressure equalizing device tending to prevent fluctuations in the pressure at the pump outlet. The location of the chamber L at the outlet side of the port G^3 prevents the volumetric capacity of this chamber from being a factor retarding the rate at which the compressor outlet pressure increases in starting.

The compressor and its driving mechanism by which the tension is regulated is comparatively inexpensive to construct and install, and may readily be applied to existing printing presses and other apparatus in which such tension regulating provisions are desirable as well as to new apparatus. The apparatus is not only reliable in operation but ordinarily requires little attention. When a change in web tension is made desirable by changes in operating conditions, this is quickly and easily effected by adjustment of the hand wheel K^2 but ordinarily no adjustment of the apparatus is required as the apparatus is started, runs up to speed and is again slowed down and stopped. Since with my invention, the tension of the paper depends upon the pressure at the pump outlet, which may easily be regulated and measured, the tension maintained is a definite thing which may be known with exactness. This means in practice that apparatus equipped with my improved tension control means may operate with a tension lower than is employed with tension controlling provisions heretofore employed in which the tension maintained is more or less indefinite and unknown, and in consequence is maintained higher than is required in order to insure that the tension is high enough. Excess tension is undesirable not only because it tends to increase the frequency with which the web is broken, but also because it increases the driving power required for drawing the paper through the apparatus and involves unnecessary wear due to friction.

The modified form of my invention illustrated in Figs. 3 and 4 differs from that shown in Figs. 1 and 2 in that friction pulleys DA are substituted for the friction belts D . Each friction wheel DA is journaled in the free end of the supporting arm E and is connected to a sprocket wheel or pulley D^{20} over which a corresponding sprocket chain or belt runs to and about a sprocket wheel or pulley D^{10} secured to the corresponding end of the pump shaft C' . With the form of my invention shown in Figs. 3 and 4, the parts should be proportioned and arranged so that each friction wheel DA will engage with the roll D when

the latter is very small as shown in dotted lines in Fig. 3.

While in general the delivery outlet pressure of the compressor should remain constant when the speed of the compressor is proportional to that of the web as it is with the apparatus shown, it is sometimes found desirable to reduce the tension when the supply roll is nearly unwound. At that time irregularities in the contour of the roll sometimes develop which tend to make the feed a little irregular and as a result makes a lower average tension desirable to avoid a momentary increase in tension to the web breaking point. To take care of this condition I have devised means shown in Fig. 6 for automatically reducing the compressor outlet pressure when the supply roll is nearly unwound. The controlling valve shown in Fig. 6 differs from that shown in Fig. 5 only in that the tension adjusting screw K' is not threaded through the outer end of the tension G^4 of the valve casing but through a cap member M fitting over the outer end of the extension G^4 . The cap member M is normally held against the end of the valve casing extension G^4 by a spring M' surrounding the extension G^4 and acting between a shoulder G' at the outer end of the extension, and a shoulder or flange M' at the inner end of the cap member M . The spring should be a stiff spring and with the parts in the position shown in Fig. 6 should be under tension greater than the maximum tension imparted to the spring I so that normally, the cap M is seated against the end of the extension G^4 and the tension of the valve controlling spring I is wholly under the control of the hand wheel K . When the roll is nearly unwound, however, the cap member M is automatically moved outward against the tension of the spring O to thereby relieve the tension of the spring I and correspondingly reduce the compressor outlet pressure. The means provided for thus moving the cap member M comprises a lever O journaled at O' and having bifurcated arms engaging trunnions M^2 carried by the cap member M . Another arm of the bell crank lever O is in position to be engaged by a cam extension E^{10} of the arm E of the power transmitting mechanism as the arm E moves into the position occupied by it when the supply roll is nearly exhausted.

Certain generic features of invention possessed in common by the apparatus disclosed herein and by other forms of apparatus devised by me are claimed in my co-pending application, Serial No. 508547 filed at even date herewith.

While in accordance with the provisions of the statutes I have illustrated and described the best form of my invention now known to me, it will be apparent to those skilled in the art that changes may be made

in the form of the apparatus disclosed without departing from the spirit of my invention as set forth in the appended claims, and that certain features of my invention 5 may sometimes be used to advantage without a corresponding use of other features.

Having now described my invention, what I claim as new and desire to secure by Letters Patent, is:

10. 1. The combination with means for advancing web or strand-like material, of means controlling the tension of said material comprising a pump, driving means therefor engaging the material and thereby driving the pump at a speed proportional to that at which the material is advanced and means tending to maintain constant the force required to drive the pump notwithstanding variations in pump speed.
15. 2. The combination with means for advancing web or strand-like material, of means controlling the tension of said material comprising a pump, and driving means therefor engaging the material and thereby driving the pump at a speed proportional to that at which the material is advanced, and means for maintaining an approximately constant pump outlet pressure notwithstanding variations in pump speed.
20. 3. The combination with means for advancing web or strand-like material, of means controlling the tension of said material comprising a pump driven by the tension of the material at a speed proportional to the speed at which the material is advanced, and a valve casing formed with two chambers one of which is connected to the compressor outlet and the other being provided with an outlet port, a port connecting the two chambers, a valve member controlling said ports and loaded with a tendency to close, but tending to open under the fluid pressure in the casing, and arranged to open the last mentioned port before opening said outlet port as the outlet pressure builds up in starting.
25. 4. The combination with means for advancing web or strand-like material, of means controlling the tension of said material comprising a pump driven by the ten-

sion of the material at a speed proportional to the speed at which the material is advanced, and a valve casing formed with two chambers one of which is connected to the compressor outlet and the other being 55 formed with an outlet port, a port connecting the two chambers, a valve member controlling said ports and tending to open under the fluid pressure in the casing, and arranged to open the first mentioned port 60 before opening the second mentioned port, and means for impressing a regulable force on said valve member tending to close it.

5. Means for controlling the tension of a travelling web comprising in combination a pump adapted to be driven by said web, a valve regulating the pump outlet pressure and comprising a valve casing formed with a chamber connected to the pump outlet and with a second chamber, and with an escape 70 port from the last mentioned chamber and with a port connecting the two chambers, a movable valve controlling said ports and subjected by the fluid pressure in the casing to a force tending to open said ports and arranged to open the connecting port before opening the outlet port, and provisions for subjecting said valve member to a regulable force tending to hold it in its closed position.

6. The combination with apparatus comprising means for supporting a roll of material wound about a roll spindle and for engaging the material and unwinding it from the roll, of means for putting the material under tension comprising a pump, means for driving the pump by force transmitted through the material at a speed proportional to the speed at which material is unwound from the roll, and means regulating the pump outlet pressure including provisions responsive to the amount of material on the roll for reducing said pressure when the amount of said material becomes very small.

Signed at New York, in the county of New York and State of New York, this 17th day of October A D. 1921.

CHARLES E. CARPENTER.
